UNITED STATES PATENT OFFICE.

FREDERICK COATES, OF CINCINNATI, OHIO, ASSIGNOR TO RICHMOND FIREPROOF DOOR COMPANY, OF RICHMOND, INDIANA, A CORPORATION OF INDIANA.

TUBE-FORMING DIE.

Application filed November 1, 1923. Serial No. 672,127.

This invention relates to the formation of flat strips of metal in tubular or substantially tubular shape, and has special reference to completing dies for an apparatus, such as is 5 described in my copending application filed of even date herewith, and bearing the Serial Number 672,126, filed November 1, 1923.

In the copending application, there has been described an apparatus for forming the 10 partially complete tubular shape, and the principal object of the present invention is to provide dies suitable for use in such an apparatus as there described, which will be adapted for completely forming the tubular 15 shapes desired.

In the companion application the apparatus shown combines the effect of drawing dies and hammering dies or pressing dies. In the present instance, the same main dies 20 are used, and in connection therewith the delivery ends of these dies are peculiarly formed so that the material may be completely bent to its entirely finished form even though it be in the form of a closed tube.

25 With the above and other objects in view, this invention consists of a novel die arrangement wherein completely tubular forms may be produced from strip material by a combined drawing and hammering operation.

30 In the accompanying drawings there is illustrated a pair of dies suitable for this purpose, and a variety of forms which may be produced by such dies, like characters of reference being employed to illustrate like parts in the several views. In the drawings,

Fig. 1 is a side elevation of a pair of dies constructed in accordance with this invention.

40 Fig. 2 is a section on the line 2—2 of Fig. 1. Fig. 3 is a section on the line 3—3 of Fig. 1.

Figs. 4 and 5 illustrate certain forms which may be produced in this manner and the cross section of the dies for producing 45 them, such cross-section being taken on lines corresponding to the line 3—3 of Fig. 1.

Figs. 6 to 9 inclusive illustrate sections at successive points in the dies for forming the complete tube and the steps in its formation.

50 In this form of the device, the main dies are indicated at 10 and 11, and correspond in their structure and function to the dies

shown in the companion application, one of these dies such as the die 10 being, as in the companion application, oscillatable toward 55 and from the remaining die such as the die 11, it not being deemed necessary to illustrate the machinery employed for this purpose. However, the die 11 is continued rearwardly as at 12, and the die 10 has a rearwardly 60 projecting tongue 13 fitting in the rear portion 12 of the die 11. It will perhaps be best understood how the device operates if it be assumed that it is desired to manufacture such a tubular form, as is shown in 65 Fig. 4. In this form, the main parts of the dies 10 and 11 act to bend the flat plate 14 up at each edge as shown at 15 in Fig. 2. As this trough shape form passes rearwardly 70 it engages the sides 16 of the auxiliary bending member 12 which assists in raising the side portions. The floor of the die 11 at the rear portion is provided with a slot 17 having a rearwardly and downwardly inclined bottom 18, and the tongue 13 is correspondingly shaped to fit within the slot. Under 75 these circumstances, the central portion of the trough shape partially finished member will be bent down so that the sides will fold up, as shown at 19 in Fig. 3, thus overlapping the portions 15, as also shown in that figure. Thus the rear portions of the dies 80 constitute bending dies, while the front portions constitute forming dies.

There has thus been provided a simple and 85 efficient device of the kind described and for the purpose specified.

It is obvious that minor changes may be made in the form and construction of the invention without in any way departing 90 from the material spirit thereof. It is not, therefore, desired to confine the invention to the exact form herein shown and described, but it is wished to include all such as properly 95 come within the scope claimed.

Having thus described the invention, what is claimed as new, is:

Dies for producing tubular forms from strip material stock, comprising a pair of relatively oscillatable main forming dies having complementary confronting faces merging gradually in cross-section from the cross-section of the stock to a cross-section of the 100 required shape opened out to trough-like

form, cooperating extensions on said dies for bending the sides of the trough-like form toward each other to cause the same to assume tubular form, one of said extensions being provided with a groove merging from a shape conforming to the central portion of the trough-like partially formed tube by

a gradual and regular deepening of the groove and contraction of its sides to a shape conforming to the same portion of the tube, the other extension being complementary thereto.

In testimony whereof I affix my signature.

FREDERICK COATES.
